(57) **CLAIM**

The ornamental design for a video image display for mobile phone, as shown and described.

DESCRIPTION

FIG. 1 is a perspective view of a video image display for mobile phone;

FIG. 2 is a front view of the video image display for mobile phone of FIG. 1;

FIG. 3 is an enlarged front view of the video image display for mobile phone of FIG. 1, but shown without the mobile phone in broken lines; and,

FIG. 4 is a perspective view of a second embodiment of the video image display for mobile phone.

The broken line showing of portions of a mobile phone is included for the purpose of illustrating environmental structure and forms no part of the claimed design.
